(57) **CLAIM**

The ornamental design for an automatic water faucet system, as shown and described.

DESCRIPTION

FIG. 1 is a top plan view of an automatic water faucet system showing my new design;

FIG. 2 is a front view thereof;

FIG. 3 is a bottom view thereof;

FIG. 4 is a right side view thereof;

FIG. 5 is a rear view thereof;

FIG. 6 is a sectional view taken on the line 6—6 in FIG. 2, with internal configuration omitted;

FIG. 7 is a sectional view taken on the line 7—7 in FIG. 2, with internal configuration omitted;

FIG. 8 is a perspective view thereof; and,

FIG. 9 is a perspective view thereof, shown mounted on a washstand.

The broken line showing of the washstand in FIG. 9 is for illustrative purposes only and forms no part of the claimed design.
